US0D1028219S

(12) **United States Design Patent** (10) Patent No.: **US D1,028,219 S**
(45) Date of Patent: ** May 21, 2024

(54) **END-EXPIRATORY BAG COLLECTION**

(71) Applicant: **Hui Yu En Technology (Shenzhen) Co., Ltd.**, Shenzhen (CN)

(72) Inventors: **Lei Yang**, Shenzhen (CN); **Bangxiong Luo**, Shenzhen (CN); **Jingting Luo**, Shenzhen (CN); **Quanfeng Zhang**, Shenzhen (CN); **Jinbo Huang**, Shenzhen (CN)

(**) Term: **15 Years**

(21) Appl. No.: **29/854,643**

(22) Filed: **Sep. 27, 2022**

(30) **Foreign Application Priority Data**

Jun. 15, 2022 (CN) 202230367756.5

(51) **LOC (14) Cl.** **29-02**

(52) **U.S. Cl.**

USPC **D24/110**; D24/118

(58) **Field of Classification Search**

USPC D24/108, 110, 110.1–110.6, 113, 114, D24/118, 121, 128–130, 164; 604/408, 604/410

CPC A61J 1/1462; A61J 1/1475; A61J 1/2027
See application file for complete search history.

(57) **CLAIM**

The ornamental design for an end-expiratory bag collection, as shown and described.

DESCRIPTION

FIG. 1 is a perspective view of an end-expiratory bag collection showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict portions of the end-expiratory bag collection that form no part of the claimed design.

1 Claim, 8 Drawing Sheets
